BICYCLE HANDLEBAR

Carlton P. Pawsat and Robert F. Humlong, Maysville,
Ky., assignors to Wald Manufacturing Company, Inc.,
Maysville, Ky.

Continuation-in-part of design application Ser. No.
23,640, June 24, 1970. This application Feb. 2,
1971, Ser. No. 112,096

Term of patent 14 years

Int. Cl. D12—16

U.S. Cl. D90—11

FIG. 1 is a front elevational view of a bicycle handlebar which shows our new design.

FIG. 2 is a perspective view thereof.

FIG. 3 is a vertical sectional view taken on line 3—3 of FIG. 1.

FIG. 4 is a perspective view of a second modified form of bicycle handlebar which shows our new design.

FIG. 5 is a perspective view of a third modified form of bicycle handlebar which shows our new design.

FIG. 6 is a perspective view of a fourth modified form of bicycle handlebar which shows our new design.

FIG. 7 is a perspective view of a fifth modified form of bicycle handlebar which shows our new design.

This is a continuation-in-part of our design patent application, Ser. No. D. 23,640, filed June 24, 1970, now abandoned.

We claim:

The ornamental design for a bicycle handlebar, as shown and described.
